TRAIN CONTROL SYSTEM

Alfred Ernest Hudd, Evanston, Ill., assignor, by
mesne assignments, to Associated Electric
Laboratories, Inc., Chicago, Ill., a Corporation
of Delaware

Application October 6, 1926. Serial No. 139,794

43 Claims. (Cl. 246—63.)

The present invention relates in general to train control systems and more particularly to systems of the intermittent inductive type.

It is well known that the braking curve of a vehicle or train varies, with the grade conditions, being proportionately longer for down grades and proportionately shorter for up grades.

Speed control systems of the general type to which the present invention relates employ a controlling element by which the speed of the vehicle can be regulated as desired, and this controlling element, which is preferably a cam, has an outline and a normal speed of movement calculated with reference to normal, that is to say, a level grade condition, whereby the speed reduction curve will conform to the normal braking curve. However, in order that this same conformity may be maintained on condition of down or up grade, it is necessary that the rate of movement of the controlling element be appropriately varied, the movement of said element being retarded for down grade conditions because of the greater length of the braking curve and being accelerated for up grade conditions because of the shorter length of the braking curve. By such regulation of the rate of movement of the controlling element it is possible to take the fullest advantage of track capacity while at the same time to fully conform to conditions of safe running.

One of the main features of the present invention has to do with the provision of means for causing the rate of movement of the speed controlling element to be determined just before the vehicle enters each caution block, and in the provision of means for causing the rate of movement, while passing through the block, to be such as to only require the vehicle to keep within the true braking curve of that block.

A second feature of the system has to do with the provision of means whereby the system discriminates between "absolute stop signals" and "stop signals" which may be passed at low speed after an acknowledgement has been made by the engineman.

A third feature has to do with the provision of a system in which cab signals for conveying all necessary indications to the engineman are provided, which renders the system perfectly adaptable for operation without wayside signals between interlocking, crossing loops, etc.

Other features include the provision of an improved type of trackway element for transmitting controlling impulses from the trackway to the vehicle, an improved inductor responsive to

such impulses, and the utilization of a flexible element for picking up the impulses transmitted.

Other features have to do with the provision of a system in which the design and construction of the mechanism used to accomplish these results is simple, inexpensive, and sound in fundamental principles, both mechanically and electrically.

The invention is illustrated in the accompanying drawings, in which—

Figs. 1, 2 and 3 taken together diagrammatically illustrate the speed controlling mechanism applied to a vehicle.

Fig. 4 illustrates details of construction of certain parts of the apparatus not very clearly shown in Fig. 2.

Fig. 5 illustrates the speed control indicator which is carried in the cab of the vehicle.

Fig. 6 is a chart illustrating several sections of trackway, the speed reduction curves which must be closely followed when passing through such sections when caution signals are passed, and trackway elements with controlling circuits superimposed on an assumed existing signalling system.

Fig. 7 shows a section of track in elevation with a trackway element fixed thereto. The trackway element is a sectional view taken on line A—B of Fig. 8. On the trackway sufficient of the locomotive is illustrated to enable the showing of an end view of the locomotive inductor connected to a journal box of the locomotive.

Fig. 8 is a side view in elevation, of Fig. 7, except that in Fig. 8, no part of the locomotive wheel is shown and the track magnet is shown complete, a section of the covers of the inductor and magnet only, being broken away.

Fig. 9 is a top view of the locomotive inductor shown in Figs. 7 and 8.

Fig. 10 is a side view of the magnet 121 shown in Figs. 3 and 8.

Before describing the operation of the system as a whole it is considered advisable to describe the construction and function of the apparatus shown in the various figures. The electro-pneumatic valve EPV shown in Fig. 1 is of the general type used on locomotives in train control systems, while the associated "actuator" consists of a cylinder 11, piston 12 and special brake handle 13 connected to an existing standard type 105 brake valve.

The speed controlling mechanism shown in Fig. 2 is in practice suitably mounted and enclosed in housings located on the locomotive. Included in this equipment is a speedometer hav-

ing a governor 55 and speed indicating disk 53 driven by a shaft 54, which is permanently geared to an axle of the locomotive through the medium of a torque device 83—87 (Fig. 3), flexible shaft 58, bevel gears 89 and 90 and shaft 103.

Cooperating with this speedometer is a permissive speed indicating arm 65 carrying a pair of brake controlling contacts 52 adapted to be actuated by the speedometer disk. The arm 65 is arranged to be normally held in an elevated position by a brake control magnet 40 but is arranged to be released and lowered at varying rates dependent on the character of the trackway sections encountered.

The rate of movement of arm 65 with respect to the rate of movement of the train is varied by mechanism under control of a grade selecting magnet 41. This magnet becomes deenergized when leaving a section to permit a geared sector 48, carried by it, to engage a pinion 78 continuously driven by pinion 78', gears 60', worm wheel 60, worm 62, shaft 58, worm wheel 57 and worm 56 on the speedometer shaft. After a certain distance of movement of the train a pin 77 engages a link 70 or 70', depending on the direction of movement, and if the grade selecting magnet 41 has not been re-energized this pin moves the link engaged, towards the periphery of a pair of clutch surfaces 61 (see Fig. 4). At the proper time, brake magnet 40 is deenergized and clutch magnet 59 is energized as will be later described, to pivotally secure the link and armature 46 of magnet 49 between the clutch surfaces before they have had time to fall. The armature 46 and the associated permissive speed indicating arm are then carried downward at a rate jointly dependent on the speed of the train and the distance from center at which the link was connected to the disks 61.

The permissive speed indicating arm 65 is pivoted to a slidable member 63 and is of such a shape that by the sliding of this member, by means of screw 64, the permissive speed indicating arm may be lowered or raised to normally indicate any desired maximum permissive speed. The changing of the pivot with respect to trigger 69 is also effective to change the rate at which the trigger will operate arm 65. The lower the arm the less it will be moved by trigger 69 and the rate of movement will be decreased. This is true because the lowering of the arm 65 increases the distance between its pivot and the point of contact of the trigger.

The torque detecting device 83—87 is shown in its active position and functions in conjunction with a magnet 82 to guard against the locomotive being used when the driving connection between the axle and speedometer shaft is broken.

Before describing the operation of the system in detail it is believed advisable to explain the structure and principle of operation of the locomotive inductor and cooperating track magnet, and for this purpose reference is made to Figs. 7, 8 and 9.

The inductor unit includes a bracket 102, one end of which is secured to a portion of the journal box 106 of a locomotive and the other of which is provided with a pole piece or magnetic element for attracting the inductor armature 105. A collector brush 97 is secured to one end of a bracket 103 which is made of iron and is provided, at its other end, with a pole piece for attracting the armature 105 away from the pole piece extending from bracket 102. This col-

lector brush 97 and part 103 are also secured to the journal box by a webbed member 101 made of brass or other non-magnetic material. Since the brush 97 is flexible it may be located so that it comes into very close proximity with the trackway elements as it passes over them, and therefore forms an efficient path for the flow of magnetic flux between them. A non-magnetic plate 120 is secured to the brackets 103 and 102 and acts as a support for a horse shoe magnet 121 (see Figs. 3 and 8) and for the contact screws 122 and 123, both of which are insulated from the support 120. The armature 105 is pivotally secured by a bracket to the upper or south pole of the horse shoe magnet, in an efficient magnetic circuit therewith, so that the armature itself becomes of the same polarity. The extensions of 102 and 103 to which pole pieces are secured are located in close proximity to the north pole of the horse shoe magnet, so that the pole pieces on the brackets 102 and 103 are normally of the same polarity as the lower pole piece of the horse shoe magnet. This causes the armature 105 to be held biased to either pole piece to which it is moved. Secured to the pole piece on bracket 103 is a winding 124 which is effective when energized to strengthen the existing polarity in its pole piece and to weaken or reverse the polarity in the pole piece associated with bracket 102 so that the armature will be attracted to the pole piece of bracket 103, if it is not already in this position.

A suitable non-magnetic cover 105' is provided which cooperates with a base plate 107 and protects the mechanism against weather.

The trackway magnet for influencing the inductor armature, independent of the associated winding 124, will now be described. Two cobalt steel permanent magnets 112 and 112' are secured within a non-magnetic housing 110 by special bolts 106' and 111 and associated clips 113 and 113'. The upper ends of these bolts are brought out through appropriate openings in the housing 110 and are flush with the outside thereof. The bolt 111, in addition to securing one end of the magnet to the housing, is also utilized to secure the entire unit to a rail of the trackway through the medium of an iron clamp 114 and associated hook bolts 115. The clamp 114 is so constructed that it secures the housing of the track magnet to the rail, but a distance therefrom of approximately 3 inches and is of such proportion as to form an efficient magnetic circuit between the rail and that end of the permanent magnet. The upper surface of bolt 106', which forms the opposite pole piece for the permanent magnet lies in a plane parallel to the top of the trackway, and the end of the housing 110 extending to the right, as illustrated in Fig. 8, is secured to the rail by a bracket similar to 114 except that, there is no magnetic connection at this point, non-magnetic material being used. The construction of those trackway elements using electromagnets is the same except for the substitution of an electromagnet for the permanent magnets shown.

If we assume that the pole piece 125 represents the north pole of the permanent magnet and that the brush collector 97 of the inductor passes thereover, a magnetic circuit for causing armature 105 to move to the right will be completed as follows: from pole piece 125, collector brush 97, iron bracket 103 and its associated pole piece, and from the south pole of

the permanent magnet represented by the trackway rail, the wheel of the locomotive, its axle and the associated journal box 196, iron bracket 102, and its associated pole piece. Since the 5 pole piece associated with bracket 102 is now associated with the corresponding poles of each of the permanent magnets the magnetic attraction for the armature 105 will be materially increased, while the other pole of the trackway 10 magnet will be associated with the pole piece attached to bracket 103, neutralizing the normal polarity produced in it by the lower pole of magnet 121. The armature 105 will therefore be shifted to the right when the inductor brush has 15 passed beyond the permanent magnet trackway element and the polarity of the pole piece associated with the bracket 103 will again be determined by the polarity of the lower pole of magnet 121, but without effect, as the armature 105 is now biased to the right by the pole piece 20 associated with bracket 103, which has the same attractive force as the pole piece on the bracket 102.

Before going into the operation of the equipment on the locomotive under the influence of the various trackway elements, an explanation will be made of the locomotive circuits.

The various circuits and apparatus of Figs. 1, 2 and 3 are shown under normal running conditions in which conditions the detector relay 82, electro-pneumatic valve magnet 22, high-speed relay 25, caution relay 33, brake control magnet 49, and grade selecting magnet 41, are all normally energized by current from a single twelve volt battery which is carried on the locomotive. In order to make the circuit disclosure as simple as possible this battery has been diagrammatically and repeatedly shown, with its positive pole grounded.

40 The relay 82 is energized from battery applied through the contact springs 30 of the clutch device to prevent the geared sector carried by its armature 93 from being driven by worm 91.

The electro-pneumatic valve magnet 22 is energized over a circuit extending from battery through contact springs 96, conductor 76, contacts 52, conductor 25, winding of magnet 22, conductor 23, upper contacts of the acknowledging switch K, armature and contact 35 of caution relay 33, and the working contact and armature 27 to ground. An alternate path over which this magnet may be held energized, when the train is at a stop and contacts 27 are opened, extends through contacts 35, conductor 24 to ground through contacts 81.

60 The high speed relay 25 is shown energized over a locking circuit extending from battery through contact 42 of the grade selecting magnet, the lower winding of relay 25 and the contact and grounded armature 23 of this relay. This relay was originally energized by the movement of the armature 105 of the pickup relay to the right, which occurred when the relay passed over a permanent magnet. This circuit extended from battery supplied through contact 42, the upper winding of relay 25, conductor 74 and the right contact and grounded armature 105 of the pickup relay.

70 The caution relay 33 at this time is held energized over a locking circuit extending from battery, through contact 43, the winding of relay 33 through its front contact and grounded armature 34. This relay was originally energized from the same battery, ground having formerly been supplied to it through the lower contacts of

switch K, conductor 68 and contacts 44 at a time when the right portion of armature 46 of magnet 40 was in its highest position.

The grade selecting magnet 41 is energized only through a circuit including conductor 75 and the grounded inductor armature 105 in its initial position and, therefore, releases its armature 47 and the sector 48 carried by it every time the locomotive passes over a permanent magnet and is reoperated by passing over an energized trackway electro-magnet, the respective polarities being arranged accordingly. The reset coil 124 is normally deenergized and only comes into action at "absolute stop" signals, as will be subsequently described.

A permanent track magnet and two electromagnets are placed alongside the track at the exit of each block, and a third electromagnet is placed just within the entry of each block, as shown in Fig. 6.

90 Referring now to Fig. 6, explanation of the various trackway circuits will be made. In the illustration given a locomotive is assumed to be traveling toward the right and is located in the block farthest to the right, with a second vehicle 100 following in the second block to the rear of the first vehicle. Under these conditions current ordinarily supplied to the three position relay 150 is shunted therefrom by the locomotive and the relay 150 assumes its neutral position, as shown. 105 With the relay 150 in the neutral position the direction of current flow to a similar three position polarized relay in the block to the rear (winding not shown) is such that its armatures 151 and 152 move to the right into the position 110 shown. With the armatures 151 and 152 of this latter relay in this position the current flow to the polarized relay 153 in the next block to the left is such that its armatures are moved to the left which is opposite to the position of the armatures 151 and 152.

115 Under these conditions it will be noted that the road side inductors of the blocks having their semaphores in "clear" position will have their number 1 electromagnetic trackway elements included in the circuit with the trackway battery when the associated approach relay 155 becomes energized. This, it will be understood, occurs when a vehicle enters the block when a 120 circuit may be traced from the lower half of the trackway battery through the winding of relay 155, the upper rail, through the vehicle axle and wheels, the lower rail, the lower armature of the polarized relay and its left contact to the other terminal of the lower half of the 125 trackway battery. Upon completion of this circuit the relay 155 actuates and completes the second path over the above traced circuit which includes the upper and lower armatures of the polarized relay 153 and the #1 electromagnetic 130 trackway element. The block which has its semaphore indicating "caution" has a circuit prepared for the #2 electromagnetic trackway element of that block. This circuit extends from 135 the lower half of the trackway battery through the right contact and armature 152, armature 151 and its right contact, the winding of the #2 electromagnetic trackway element, the armature and front contact of the approach relay, and 140 back to the lower half of the trackway battery. Since the polarized relay 150 across the rails of the block occupied by the vehicle is shunted out its armatures are in the neutral position.

145 In this position the circuit for the third electromagnetic trackway element is prepared and 150

if the associated approach relay is operated the circuit of the third electromagnetic element is completed, from the upper half of the associated trackway battery, middle contacts and armatures of relay 150, in neutral position, winding of the #3 electromagnetic element, and through the armature and contact of the associated approach relay back to battery. Where an absolute stop must be made this latter electromagnetic trackway element is omitted.

If a train enters a block in which the semaphore or roadside signal indicates a clear condition, as illustrated by the first block signal shown in Fig. 6, the following operations will take place; the inductor on the locomotive upon passing the permanent magnet track element will deflect its armature from its initial to its alternate position thereby breaking the energizing circuit of the grade selecting magnet 41. The armature of the magnet 41 does not fall a sufficient distance to break either pair of its contacts, because, before this can occur, the portion 51 of the sector 48 carried by the armature, engages the pinion 73. Ten feet of travel of the train will cause the sector 48 to be rotated sufficiently to cause it to rotate off teeth 51 and drop into engagement with pinion 73 through its teeth 50 and thereby permit the armature 47 to open its contacts 42. Before the locomotive has passed ten feet beyond the permanent magnet the #1 electromagnet trackway element will be encountered. Since this electromagnet is energized when encountered under clear conditions, as shown by the circuits of Fig. 6, the inductor armature 195 is deflected back to its initial position. This causes the re-energization of magnet 41 and the consequent restoration of sector 48 before contacts 42 or 43 have opened, preventing anything further occurring at this time.

If now the locomotive is about to enter a caution block, as indicated by the second wayside signal shown in Fig. 6, a permanent magnet will be again effective to bring about the deenergization of the grade selecting magnet 41. Since a caution block has been entered however, the electro-magnet wayside element #1 which is located within ten feet of the permanent magnet will be deenergized at this time and the #2 electro-magnet energized instead as illustrated in Fig. 6, and therefore, pinion 73 continues to rotate the sector 48. As soon as the locomotive has traveled ten feet, the sector 48 rolls off from portion 51 onto its portion 50 thereby permitting the armature of magnet 41 to drop sufficiently to open the locking circuit of the high-speed relay 25 at its contacts 42. This relay upon becoming deenergized, at its contacts 28 opens another point in its locking circuit, at its contacts 26 removes ground from one of the branch conductors extending to the magnet 40, at its contacts 27 disconnects ground from a branch circuit extending to the winding of the electro-pneumatic valve magnet 22, at its armature 30 opens the circuit of lamp G and closes that of Y; and at contacts 29 closes a point in the operating circuit of the clutch magnet 59. At the same time that sector 48 rolled off its portion 51 the pin 77, carried by it, engaged the arm 70. As the locomotive proceeds arm 70 will be moved toward the periphery of the disks 61 (see Fig. 4). When the arm 70 is at some intermediate point however, the #2 electro-magnet will be encountered by the locomotive and as a result in-

ductor armature 105 will be deflected from its alternate to its initial position.

Since however, relay 25 is deenergized at this time, the switching of the inductor armature from its alternate to initial position opens the only remaining circuit of the brake control magnet 40, the circuit of this magnet having extended from battery through the winding of 40, contacts 36 of the relay 33, and the inductor armature in its alternate position and ground. The armature of the magnet 40 is prevented from falling however, by the energization of the clutch magnet 59 which occurred when its circuit was completed from ground through the armature 105 of the inductor in its initial position, conductor 75, contacts 29 of relay 25 and contacts 37 of the relay 33. By referring to Fig. 4, it will be noted that the arm 70 is ordinarily suspended between two flat surfaces 61 which are under the control of the clutch magnet 59. When the magnet 59 is energized the arm 70 is secured at a point intermediate to the recessed portion of the flat surfaces 61 and their periphery, the exact location being dependent upon the gradient and length of the particular block in which the locomotive is traveling. This distance is determined by the distance between the permanent track magnet and the #2 electro-magnet.

As the locomotive proceeds the arm 70 and its connected armature 46 are gradually carried downward with the result that the pivoted member 69 and the permissive speed indicating arm 65 are lowered by cam 178 at a rate of speed dependent first upon the speed of the train and second, upon the speed reduction curve selected, as determined by the distance from the center of the disks 61 that arm 70 is being held.

Since the link 70 may be secured between the surfaces 61 at any point, determined by the spacing of the #2 electromagnet with respect to the permanent magnet, the rate of falling of arm 65 for a given vehicle speed is infinitely variable and can be automatically adjusted at the entrance of each block in order to force the engineman to keep his vehicle at or below a speed which is commensurate with the braking distance to the stop signal.

In the foregoing, only the controlling functions of the inductor and its relation to "clear" indications and in the initiation of the grade selection when "caution" indications are encountered have been taken into consideration. The actual control of the brakes of the train will now be taken up.

As previously stated the existing standard type of automatic brake valve is equipped with an "applicator" which consists of a cylinder 11, piston 12 and special brake handle 13. An appropriate air pipe 14 connects the cylinder to the electro-pneumatic valve controlled by sole-noid 22. The cylinder 11 is normally open to atmosphere through valve 15 and opening 16, and air pressure from the main reservoir is normally acting against the diaphragm 17 to keep the valve 18 closed and valve 15 open. An outlet 140 20 is provided in the high pressure chamber 19, but this is normally closed by a magnet 22.

The operation is as follows:

When the EPV magnet 22 is deenergized, the diaphragm 17 collapses after a certain predetermined time has elapsed, the duration of which is determined by the area of valve port 20 and the inlet orifice 21. For instance, if the high pressure chamber 19 is connected to a reservoir and the orifice 21 is smaller than the port 20, then

the time element referred to can be considerably increased. In practice, however, the structure of chamber 19 and the relative areas of the ports 20 and 21 are adjusted to allow valve 18 (connected to diaphragm 17) to open in about 6 seconds after the release of the EPV magnet. A whistle W is provided for the purpose of causing an audible warning to be given immediately when valve 20 opens, the pressure in chamber 19 exhausting to atmosphere through the passage 10, so that if circumstances permit, the engineer can take action to close the valve 20 as will be described later.

It will be noted that the valves 18 and 15 are fixed to the same shaft so that the opening of 18 closes 15 and vice versa. When 18 is closed the brake handle 13 may be freely pushed back to normal "running" position as the cylinder 11 is then connected to atmosphere through valve 20 15 and orifice 16. One terminal of the magnet 22 is normally connected to the negative pole of a battery through speedometer contacts 52 and detector contacts 96. The other terminal of the magnet is normally connected to ground via 25 three branches. One branch extends through contacts 35 and 27 of relays 33 and 25, respectively; and another branch extends through contacts 35, conductor 24 and normally closed contacts 71 of the electro-pneumatic valve EPV; 30 while when the vehicle is stationary, a third path extends from ground via the zero contacts 81, conductor 24 and contacts 35 of caution relay 33. It will be noted that all of these connections to the grounded side of the battery pass through 35 the contacts 35 of the caution relay 33 and through normally closed contacts of the acknowledging key K. From the foregoing, it will be seen that so long as the speedometer contacts 52 and the detector contacts 96 are closed, the EPV 40 magnet 22 will remain energized as far as this side of its circuit is concerned.

If now the contacts 52 are set at such a height that they will not be opened unless the disk 53 on the speedometer shaft rises above a predetermined setting, say 70 miles per hour, the speedometer contacts will not be opened, unless this speed is exceeded.

If the train exceeds 70 m.p.h., disk 53 will rise and open contacts 52 causing the deenergization 50 of magnet 22. Upon a consequent release of the valve 20 air is exhausted through whistle W to warn the engineer that if at this stage the speed is not reduced to 70 m.p.h. within six seconds after contacts 52 are opened a brake application 55 will take place, because at the termination of this six second period diaphragm 17 will collapse causing valve 18 to open and admit full reservoir pressure to the actuating brake cylinder 11 thereby moving the brake handle 13 to service 60 position.

Since the circuit of magnet 22 has not otherwise been disturbed, as soon as the speed has been reduced sufficiently to permit contacts 52 to again close, the magnet 22 will again become 65 energized. As soon as the pressure in chamber 19 becomes sufficient valves 15 and 18 are restored and the engineer may then restore the brake handle to running position.

On passing a "distant" or caution signal, 70 (which indicates that the next signal is at "stop") the inductor armature is deflected from its initial to its alternate position, as previously explained, to open the circuit of the grade selecting magnet 41 permitting the sector 48 to fall upon the pinion 78, which rolls the sector 75

to an intermediate position contingent on the distance between the permanent magnet and #2 electromagnet of the track magnets, as hereinbefore described. Consequently the holding circuit of relay 25 is broken and it therefore becomes deenergized as previously explained.

On passing over the electro-magnet #2, the inductor armature 105 is restored to its initial position, but as relay 25 is deenergized at this time, its contacts 26 for holding magnet 40 energized independent of the inductor armature are open and therefore, magnet 40 is now deenergized also.

Simultaneously with the deenergization of magnet 40, the clutch magnet 59 is energized over a circuit extending from ground, through the inductor armature 105 in its initial position, conductor 75, contacts 29 of relay 25, and contacts 37 of relay 33. As previously explained, the operation of the clutch magnet 59 pivotally secures the link 70 and the connected armature 46 of magnet 40 so that the armature and the arm 65 controlled by it through the medium of lever 69 will be gradually lowered at a rate dependent on the position of the link 70 with respect to the 100 axis of the surfaces 61, as previously described.

If now the engineman reduces the speed of the train sufficiently to prevent the speedometer disk 53 from opening the contacts 52, no automatic brake application will be made, but if he fails to do so the circuit of the EPV magnet 22 will be broken, which, as previously explained will cause the service brake application to be made after a six second interval.

It may be mentioned at this time that the 110 whistle W will be operated during the six second period, and therefore, if the engineman is alert he will be able to reduce the speed of the train and prevent any automatic brake application taking place. On the other hand, if he fails, at 115 the termination of the six second interval valves 15 and 18 will be moved to their alternate positions and the brakes will automatically be applied.

Since at this time the high speed relay 25 is 120 deenergized and zero contacts 81 are open, the only path over which ground was being supplied to the EPV magnet 22 was through the valve contacts 71 which also opened when the valve operated; therefore, the brake application will 125 be made regardless of any act on the part of the engineman and there is nothing he can do but wait until the train has come to a stop. When this occurs, the zero contacts 81 close and a circuit is reestablished for the EPV magnet, (contacts 52 having closed as soon as the speed of the train was reduced) the chamber 19 again builds up to full reservoir pressure and diaphragm 17 closes valve 18 which releases the air pressure in cylinder 11 to atmosphere and permits the engineer to restore the engineer's brake 130 valve running position.

Since nothing has occurred as yet to restore the arm 65, and its associated contacts 52 to their maximum position the engineer must keep the 140 speed of the train within a limit determined by the location of these contacts which may be in an intermediate position at the time the train is brought to a stop. These contacts will of course continue to move downward as the train 145 proceeds through the remainder of the block.

The amount of speed reduction necessary to prevent an automatic brake application occurring while passing through a caution block is such that at the end of the block the train will be 150

under what may be termed, low speed control which is, say a speed of 20 m.p.h. Trains upon entering blocks at the end of which a permissive stop signal is displayed, can pass the signal at the prescribed low speed providing proper acknowledgement is made. As illustrated in Fig. 6, when a signal of this character is encountered the associated #3 electromagnet is energized. This magnet is placed a distance from the permanent magnet sufficient so that, after the armature 105 is moved to the right as a result of the inductor passing over the permanent magnet trackway element, the train will travel a distance which suffices to rotate the sector 48 until it again drops and its teeth 49 engage the driving pinion. When this occurs the armature 47 drops sufficiently to open its contacts 43 causing the caution relay 33 to become deenergized as well as the high speed relay 25. The braking magnet 40, accordingly, deenergizes as it did under caution conditions; but since the relay 33, in dropping, opens a point in the circuit of clutch magnet 59, the armature 46 drops the speed control arm 65 immediately to its low speed position, opens its contacts 45 and closes its contacts 44. An instant later the energized #3 electro-magnet is encountered and the inductor armature 105 is deflected from its alternate to its initial position, but the operation of magnet 41 cannot at this time cause the restoration of the caution relay 33 or high speed relay 25. The reason for this is that relay 25 can only be reenergized through the armature 105 in its alternate position, while relay 33 can only be energized through normally open contacts of the acknowledging key K. The relay 25, it will be noted was already deenergized due to the previous caution block. The caution relay 33 upon becoming deenergized, opens the circuit of the EPV magnet 22 at contacts 35, with the result that the whistle W is sounded. At this time in addition to the whistle the relay 33 at its contacts 34 completes the circuit of the acknowledging bell AB, causing it to warn the engineer that an automatic brake application can only be avoided by his operating the acknowledging key K within the usual six second interval. Upon operating the key, its make contacts again complete the operating circuit of the caution relay 33, which locks up as before. In order to guard against the engineer permanently operating the key K, the circuit of the EPV magnet 22 is carried through break contacts of the key K, so that it is absolutely necessary that the acknowledging key be immediately restored after the operation of relay 33, otherwise the brakes will be automatically applied. It will be noted that relay 33 in operating at contacts 34 cuts off signal AB which serves to warn the engineer that it is time to release the key K.

After acknowledging, the train may continue at low speed, but the engineer must operate the key K at every subsequent permissive stop signal encountered.

At "absolute stop" signals, no #3 electro-magnets are provided and therefore, the sector 48 will be operated until it drops out of engagement with the pinion 78. Under this condition the circuit of the relay 33 is broken as before at the permissive signal, but no energizing circuit is again completed for the grade selecting magnet 41, and therefore the circuit of the caution relay 33 is broken at two points, at contacts 43 and 44, and actuation of the acknowledging key will be of no avail. The train must now be brought to

a stop before the circuit of the caution relay 33 can be again restored.

When the train is finally brought to a stop the zero contacts 104 will be closed and a circuit will be completed from battery through these contacts, conductor 73, contacts 38 of caution relay 33, conductor 72 and through the reset coil 124 associated with the inductor contact and ground. The direction of current through this coil is such that the inductor armature 105 will be restored to its initial position, with the result that the grade selecting magnet 41 is again energized and its contacts 42 and 43 are again closed.

The action of the reset coil in conjunction with the zero contacts 104 is the same as that which occurred when the inductor passed over an energized #3 electro-magnet, and the circuit of relay 33 having been prepared in this manner, the acknowledging key K may now be operated to restore the circuit of this relay so that the EPV magnet 22 may again be energized and the brakes released. After the brakes are released the train must proceed at the low speed until a set of magnets preceding a block "at clear" are encountered. Irrespective of traffic conditions in the block next encountered the permanent magnet inductor will be effective to actuate armature 105 to its alternate position, resulting in the reenergization of high speed relay 25 and the consequent reenergization of magnet 40. The armature 46 and speed control arm 65 are accordingly restored, but whether they remain so restored, are lowered under control of the train movement, or are dropped again to low speed position depends on the clear, caution, or stop condition of the block in advance, as interpreted by the condition of the subsequently encountered electromagnets of the group.

From the foregoing it will be appreciated that the train must be brought to a complete stop before it is allowed to pass a specified distance beyond a permanent magnet in cases where none of the associated electro-magnets are energized. In actual practice the engineer may pass an absolute stop signal without having the brakes automatically applied but to do so he must move toward the signal at a very slow rate of speed so that he can stop immediately within the six second period so that the zero contacts 104 will be closed before diaphragm 17 of the electro-pneumatic valve collapses.

From the foregoing it will be seen that a brake application due to exceeding the maximum speed limit may be released by reducing the speed to its normal maximum rate illustrated as being 65 m.p.h., but an application caused by overrunning the braking curve or passing stop signals without acknowledgement can only be removed by bringing the train to a standstill. Furthermore, when it has once been brought to a standstill the train can only proceed at low speed up to the next indication point, where if the #1 electro-magnet is energized, which indicates a clear condition the train can resume normal running.

An explanation will now be made of the operation of the lamp signals in the cab. During normal running through clear territory the high speed relay 25 remains energized and the green light G will be lighted over a circuit including contacts 30 of this relay, conductor 67, and contacts 45, to indicate that the traffic conditions are "clear". When a caution block is entered and the high speed relay 25 is deenergized, the green

- light is extinguished and the yellow or caution light Y is immediately lighted due to the opening of contacts 30 and closing of contacts 31. This circuit it will be seen also includes conductor 67 5 and contacts 45. When the speed of the train has been reduced at the end of the caution block the armature 46 of magnet 40 is at its lowermost position, at which time the circuit of caution light Y is broken at contacts 45 and a circuit is 10 closed through the alternate contacts 44 for the red or danger lamp signal R. These various lamp signals taken in conjunction with the audible signals and brake indicator hereinbefore referred to inform the engineer at all times under 15 what condition his train is being operated.
- In a train control system wherein the train control mechanism is operated through power transmitted from a wheel of the locomotive it is important that some provision be made to guard 20 against the locomotive being taken out on a run when the connection between the train control equipment and the wheel of the locomotive is broken. This has been accomplished in the present case by providing the torque detector, 25 previously briefly referred to.
- The flexible speedometer shaft 88 from which the train control equipment is driven is connected to the wheel of the locomotive through a unit comprising a sliding spring coupling carrying a 30 disk which is normally raised when the torque is applied to the speedometer shaft. When no torque is applied the disk is forced downward by the spring 88 and breaks a pair of contacts 80, causing the deenergization of magnet 82. 35 This allows the geared sector 94 to fall into engagement with the worm 91. If now the engine is in motion, sector 94 will be rolled out of engagement with 91 and the contacts 96, which supply battery current to the EPV magnet 22, 40 will open to cause a brake application. Under normal circumstances, of course, the train may come to a rest without opening contacts 96, because the axle comes to rest at the same time that torque is removed from the unit.
- 45 It will be noted that the permissive speed indicating arm is shown in a position with respect to the speedometer disk to indicate a permissive speed of 70 m.p.h. A passenger train traveling through a 4000 foot block, under caution conditions, with a permissive speed as indicated will cause the arm 65 to be lowered from 70 to 20 in the 4000 foot distance of travel. Now if a freight train passes through this same block under the same conditions, except that its permissive speed 50 indicating arm is positioned to indicate a maximum of 40 miles per hour the arm 65 will be lowered from 40 to 20 in the 4000 foot distance of travel due to the change of position of the fulcrum of 65. From this it will be seen that the braking curve for any vehicle is accurately enforced irrespective of its maximum permissive speed.
- 55 From the foregoing it will be appreciated that applicant has devised a train control system which is practical, and requires very little equipment compared to that required by other systems 60 accomplishing the same results.
- What is claimed is:
1. In a system of vehicle speed control, in combination, a movable speed control element, and magnetic means placed intermittently along the path of travel of the vehicle for varying the speed at which the element moves with respect to the speed of the vehicle.
  2. In a system of vehicle speed control, a locomotive equipped with speed controlling mechanism which includes an operating element whose rate of movement determines the extent of the speed reduction curve, a trackway forming a path over which the vehicle travels, said trackway divided into block sections of equal and varying lengths, and permanent and electromagnets associated with the trackway in the exit portion of each block section for determining the speed reduction curve for the succeeding section. 80
  3. In combination with a locomotive and a track over which the same travels, normally inactive speed control mechanism for the locomotive, and inductive trackway elements distributed along the trackway effective as the locomotive passes them to cause the speed control mechanism to operate at various rates of speed with respect to the speed of the locomotive. 85
  4. In a system of vehicle speed control, a speed controlling mechanism including an operating element, variable speed driving means for said element, and trackway magnet means in inductive relation to vehicle carried means for regulating the speed of the element. 90
  5. In a system of vehicle control, speed controlling mechanism including a normally inactive operating cam, in combination with a vehicle and trackway for the same, a system of speed controlling equipment in part associated with the vehicle and in part associated with the trackway, the equipment associated with the vehicle including means for permitting the vehicle to travel through all track sections, at the same maximum speed at one time and for requiring the vehicle to pass through the same sections at 100 constantly reducing restricted speeds specially characteristic of such sections at another time, said equipment influenced inductively by the equipment on the trackway at the exit of the section in a manner dependent upon the condition of a succeeding trackway section. 110
  6. In combination with a vehicle and an associated trackway, a movable permissive speed device, and permanent and electromagnets intermittently disposed along the trackway for controlling the movement of the permissive speed device at varying rates of speed with respect to the speed of the vehicle. 120
  7. In a system of control for moving vehicles, comprising normally inactive means for retarding the movement of the vehicle, a permissive speed indicator, an actual speed indicator, one of the indicators being normally inactive, inductive means placed in the path of travel of the vehicle for causing the movement of the normally inactive indicator to occur at a rate dependent upon the spacing of said inductive means, and means controlled by the movement of the inactive indicator to a predetermined relation with respect to the other indicator for causing the operation of the retarding means. 125
  8. A system of train control for moving vehicles including a normally inactive means for retarding the movement of the vehicle, a normally active actual speed indicator, a normally inactive permissive speed indicator in the path of movement of said actual speed indicator, means for causing the movement of the permissive speed indicator, means controlled by the movement of the actual speed indicator into 140 engagement with the permissive speed indicator while the same is inactive to effect the operation of the retarding means until the actual speed indicator moves out of the predetermined relation with the permissive speed indicator only, 145
  9. In a system of vehicle speed control, a locomotive equipped with speed controlling mechanism which includes an operating element whose rate of movement determines the extent of the speed reduction curve, a trackway forming a path over which the vehicle travels, said trackway divided into block sections of equal and varying lengths, and permanent and electromagnets associated with the trackway in the exit portion of each block section for determining the speed reduction curve for the succeeding section, 150.

means for effecting the operation of the retarding means when the actual speed indicator and permissive speed indicators are moved into a predetermined relation to each other, to effect the operation of the retarding means, and means for preventing any subsequent changes occurring in the relation between the actual and permissive speed indicators from affecting the operation of the retarding means in the latter instance.

9. In a system for controlling moving vehicles, a normally stationary gear, a cam having a speed of operation determined thereby, a gear continuously driven by the movement of the vehicle for operating said stationary gear and cam, and means for causing the operation of the cam to take place only after the speed of operation has been determined by appropriate movement of the normally stationary gear.

10. In a system of vehicle speed control, the combination with a locomotive and trackway divided into blocks or sections, of a series of inductor elements distributed along the exit of each section, the first of the inductor elements comprising a permanent magnet and the remaining elements comprising normally deenergized electro-magnets, a contact device on the vehicle, means on the vehicle inductively associated with said elements as the vehicle passes through each block section and effective when passing over a permanent magnet to cause the associated contact device to be deflected from one position to another and to be restored when passing over an energized electro-magnet and speed control mechanism on the vehicle controlled thereby in a manner dependent upon which one of the electro-magnets was energized when the vehicle passed over the series.

11. In a railway automatic train control system, a trackway, a vehicle for movement thereon, means on the vehicle conditioned during a certain distance of movement of the vehicle for controlling the speed thereof during a subsequent movement, and means on the trackway for governing the vehicle controlling means, the means on the trackway including two inductive members spaced longitudinally of the trackway a distance apart contingent on the control desired.

12. In an automatic train control system, including a normally inactive means which when initiated sets up a restricted speed limit and effects an automatic brake application if this speed limit is exceeded, means for transmitting a control impulse effective to start or initiate the functioning of said normally inactive means, means for transmitting a second impulse after a definite distance has been travelled to neutralize the effect of the first impulse and means effective to transmit an impulse if no other second impulse has been transmitted to cause said normally inactive means to become active and require a restriction of speed dependent on the distance between the first and last impulse transmitting means.

13. A system of train control for moving vehicles comprising means on the vehicle adapted to indicate its actual speed, means on the vehicle adapted to indicate its permissive speed, a signal normally inactive, and means for actuating said signal to give a warning when the permissive speed indicating means is about to be actuated.

14. A system of control for moving vehicles comprising means on the vehicle adapted to indicate its actual speed, a device on the vehicle adapted to indicate its permissive speed, means

for causing said permissive speed indicating device to operate and indicate different permissive speeds, a plurality of signals for informing an operator under what trackway conditions the vehicle is traveling, means for maintaining one of the signals actuated under a clear condition, means for actuating another of the signals when caution territory is entered and prior to the actuation of the permissive speed indicating means, and means for actuating a third of the signals as soon as the permissive speed indicating means has been moved a definite distance.

15. In combination with a vehicle and an associated trackway divided into varying length sections, train control equipment having means successively actuated, at the exit of each section to determine whether the vehicle will be permitted to continue through the succeeding section at maximum speed or whether its speed must be gradually reduced until it reaches a minimum speed at the end of the section, and means whereby the rate of speed reduction is determined just before entering the section.

16. In combination with a vehicle and an associated trackway divided into varying length sections, train control equipment having means for determining whether the vehicle will be permitted to continue through a section at maximum speed or whether its speed must be gradually reduced until it reaches a minimum speed at the end of the section, and means whereby the rate of speed reduction is made solely contingent upon means being operated successively responsive to the passing of predetermined points of the trackway just before the vehicle enters the section.

17. In a speed control system for railway vehicles, a track way divided into blocks, a group of inductive elements at the exit and entry of each block comprising a permanent magnet and three electro-magnets, speed control equipment on a vehicle passing over the trackway, means for starting said equipment to function each time a permanent magnet is passed, means for energizing one of the electro-magnets to neutralize the effect produced by the permanent magnet if the third block ahead is occupied, means for energizing another of the electro-magnets if the second block ahead is occupied to cause the vehicle equipment to force a speed reduction of the train down to a predetermined speed and means for energizing the third of the electro-magnets if the block ahead is occupied to cause the equipment to function to prevent the vehicle from entering that block unless an acknowledgement is made by the operator of the vehicle.

18. A system for control of moving vehicles, comprising means on the vehicle adapted to indicate its actual speed, means on the vehicle adapted to indicate its maximum permissive speed, means for causing said permissive speed indicating device to move towards a part of the actual speed indicating means to indicate a continuously diminishing rate of speed for the vehicle and to discontinue movement when reaching a permissive predetermined low speed indication, and means for adjusting the permissive speed indicating device so that its rate of movement with respect to the rate of movement of the vehicle is varied in accordance with the maximum permissive speed at which the vehicle is to be allowed to travel.

19. In a system of control for moving vehicles, a permissive speed indicating device, means for variably positioning said device in accordance

- with the maximum speed at which the vehicle is to be permitted to travel, and means for operating the device at a speed contingent partially upon the initial position of the device.
- 5 20. In a system of control for moving vehicles, a normally inactive permissive speed indicating device, means for varying the initial or normally inactive position of said device so that the same may be set to indicate any of a number 80
- 10 of desired maximum permissive speeds depending upon the character of the vehicle to be controlled, and means for driving said device from its initial position to the same predetermined 85
- 15 low speed indicating position by the same distance of movement of the vehicle irrespective 90
- of the initial setting of the speed indicator.
- 20 21. In a system of control for moving vehicles, a permissive speed indicating arm, said arm being free at one end and pivoted at the other 95
- 25 and supported at an intermediate point by means for causing the arm to indicate a continuously diminishing rate of permissive speed for the vehicle, means for lowering the support of the arm at a certain rate with respect to the rate 100
- 30 of movement of the vehicle, and means for changing the fulcrum of the speed indicating arm to various points of contact with the lever to vary the rate of movement of the indicating 105
- 35 lever with respect to the same rate of movement of the vehicle.
- 40 22. In a system of train control, a speed indicating lever pivoted at one end and supported at an intermediate point by an element for lowering it, means for changing the fulcrum of 110
- 35 the lever from one point to another to change the maximum permissive speed indicated by it and to change the rate of movement of the lever from one point to another with respect to the 115
- 40 rate of movement of the element.
- 45 23. In a system of train control, a lever pivoted at one end and equipped with a permissive speed indicating arrow at the other end and supported at intermediate points by an element for lowering the indicating lever, means for changing 120
- 50 the fulcrum of the lever from one point to another to change the maximum permissive speed indicated by the connected arrow and to change the rate of movement of the lever from one point to another with respect to the rate of movement of this element and means for varying the 125
- 55 rate of movement of the element with respect of movement of the vehicle.
- 60 24. In a system of speed control for vehicles, an inductor consisting of an armature biased to either of two positions to which it may move, and trackway elements for inductively influencing said inductor to thereby operate its armature in a manner dependent on traffic conditions, and manually controlled circuits on the vehicle 130
- 65 for also influencing said inductor under certain conditions.
- 70 25. In a system of speed control for vehicles, an inductor consisting of an armature normally biased to either of two positions, trackway elements inductively related to said inductor to cause the same to be operated, a series of trackway elements consisting of a permanent magnet and three electromagnets, the permanent magnet being effective to move the armature to its alternate position to start the functioning of the speed control equipment, and track circuits for energizing one of the electromagnets to further influence the equipment in a manner dependent on traffic conditions.
- 75 26. In combination with a vehicle and an as- 135
- soiated trackway divided into varying length sections, of train control equipment partly on the vehicle and partly on the trackway, the trackway equipment comprising a permanent magnet and two electro-magnets placed longitudinally of the trackway at the exit of each section and of a third electromagnet placed at the entrance of the next section; and the vehicle equipment consisting of an actual speed indicator, a permissive speed indicator and associated mechanism for regulating the movement of the vehicle in accordance with traffic conditions, and an actuator on the vehicle consisting of an armature normally biased to one position by a permanent magnet but deflected to an alternate position when the vehicle brings it into inductive relation to a trackway permanent magnet and restored by one of the energized electro-magnets to control the equipment on the vehicle for the purpose set forth.
27. In a system of vehicle control, a governor, means including a sliding spring clutch for transmitting motion from the axle of a vehicle to the governor, a normally energized vehicle control magnet effective, when deenergized, to cause the speed of the vehicle to be reduced, a relay having working contacts through which the circuit of said vehicle control magnet circuit passes, mechanical means for normally holding said contacts closed when the vehicle is at a standstill 105
- but ineffective after a limited distance of movement, and a circuit for said relay extending through contacts closed by the driven portion of said spring clutch to maintain said relay energized and the retarding magnet circuit closed 110
- after the mechanical means becomes ineffective to prevent the operation of the retarding means, unless the governor driving means fails.
28. In a system of vehicle control, speed control equipment partly on a trackway divided into 115
- sections and partly on the vehicle, retarding means on the vehicle, a controlling magnet having a circuit for maintaining it operated to prevent the retarding means becoming effective, a permanent magnet at the exit end of each track- 120
- way section for transmitting and a polarized magnetic pickup relay on the vehicle for receiving an impulse to cause said circuit to be opened only after the vehicle has traveled a certain distance irrespective of its speed, and an electromagnet for 125
- transmitting a second impulse to said pickup relay prior to such distance of travel to render the effect of the first impulse ineffective.
29. In a system of vehicle control, speed control equipment partly on a trackway divided 130
- into sections and partly on the vehicle, retarding means on the vehicle, a controlling magnet having a circuit for maintaining it operated to prevent the retarding means becoming effective, means at the exit end of each trackway section 135
- for transmitting and on the vehicle for receiving an impulse to cause said circuit to be opened only after the vehicle has traveled a certain distance irrespective of its speed, and means for transmitting a second impulse to said receiv- 140
- ing means to cause the circuit of said magnet to be held intact as long as the speed of the vehicle is kept under a constantly diminishing indicated permissive speed.

- means at the exit end of each trackway section for transmitting and on the vehicle for receiving an impulse to cause said circuit to be opened only after the vehicle has traveled a certain distance irrespective of its speed, means for transmitting a second impulse to said receiving means to cause the circuit of said magnet to be instantly broken, and manually operable means for restoring said circuit before the retarding means can become effective.
5. In a system of vehicle control, control equipment partly on a trackway divided into sections and partly on the vehicle, retarding means on the vehicle, a normally closed controlling circuit for preventing said retarding means from being actuated, a permanent magnet at the exit of each section for transmitting and a polarized magnetic device on the vehicle for receiving an impulse to cause said circuit to be interrupted, means for thereafter preventing said retarding means from being actuated for a predetermined interval of time, and means for again actuating said polarized magnetic device to reclose said circuit prior to the expiration of said interval.
10. In a system of vehicle control, control equipment partly on a trackway divided into sections and partly on the vehicle, retarding means on the vehicle, a normally closed controlling circuit for preventing said retarding means from being actuated, a permanent magnet at the exit of each section for transmitting and a polarized magnetic device on the vehicle for receiving an impulse to cause said circuit to be interrupted, means for thereafter preventing said retarding means from being actuated for a predetermined interval of time, and means for again actuating said polarized magnetic device to reclose said circuit prior to the expiration of said interval.
15. In a system of vehicle control, control equipment partly on a trackway divided into sections and partly on the vehicle, retarding means on the vehicle, a normally closed controlling circuit for preventing said retarding means from being actuated, a permanent magnet at the exit of each section for transmitting and a polarized magnetic device on the vehicle for receiving an impulse to cause said circuit to be interrupted, means for thereafter preventing said retarding means from being actuated for a predetermined interval of time, and means for again actuating said polarized magnetic device to reclose said circuit prior to the expiration of said interval.
20. In a system of vehicle control, control equipment partly on a trackway divided into sections and partly on the vehicle, retarding means on the vehicle, a normally closed controlling circuit for preventing said retarding means from being actuated, a permanent magnet at the exit of each section for transmitting and a polarized magnetic device on the vehicle for receiving an impulse to cause said circuit to be interrupted, means for thereafter preventing said retarding means from being actuated for a predetermined interval of time, and means for again actuating said polarized magnetic device to reclose said circuit prior to the expiration of said interval.
25. In a system of vehicle control, control equipment partly on a trackway divided into sections and partly on the vehicle, retarding means on the vehicle, a normally closed controlling circuit for preventing said retarding means from being actuated, a permanent magnet at the exit of each section for transmitting and a polarized magnetic device on the vehicle for receiving an impulse to cause said circuit to be interrupted, means for thereafter preventing said retarding means from being actuated for a predetermined interval of time, and means for again actuating said polarized magnetic device to reclose said circuit prior to the expiration of said interval.
30. In a train control system, a normally stationary element, a second element operable at a speed determined by said first element, a third element for operating said first and second elements, and means for causing the operation of the second element to occur only after the speed of its operation has been determined by an appropriate movement of the first element by said third element.
35. In a train control system, a normally stationary element, a second element operable at a speed determined by said first element, a third element for operating said first and second elements, and means for causing the operation of the second element to occur after the speed of its operation, with respect to a given speed of movement of a vehicle, has been determined by an appropriate movement of the first element by said third element.
40. In a system of vehicle control, speed control equipment partly on a trackway divided into sections and partly on the vehicle, retarding means on the vehicle, a controlling magnet having a circuit for maintaining it operated to prevent the retarding means becoming effective, means at the exit end of each trackway section for transmitting and on the vehicle for receiving an impulse to cause said circuit to be opened only after the vehicle has traveled a certain distance irrespective of its speed, means for transmitting a second impulse to said receiving means to cause the circuit of said magnet to be instantly broken, and manually operable means for restoring said circuit under either circumstance, before the retarding means can become effective.
45. In a system of vehicle control, speed control equipment partly on a trackway divided into sections and partly on the vehicle, retarding means on the vehicle, a controlling magnet having a circuit for maintaining it operated to prevent the retarding means becoming effective, means at the exit end of each trackway section for transmitting and on the vehicle for receiving an impulse to cause said circuit to be opened only after the vehicle has traveled a certain distance irrespective of its speed, means for transmitting a second impulse to said receiving means to cause the circuit of said magnet to be instantly broken, and manually operable means for restoring said circuit under either circumstance, before the retarding means can become effective.
50. In a system of vehicle control, speed control equipment partly on a trackway divided into sections and partly on the vehicle, retarding means on the vehicle, a controlling magnet having a circuit for maintaining it operated to prevent the retarding means becoming effective, means at the exit end of each trackway section for transmitting and on the vehicle for receiving an impulse to cause said circuit to be opened only after the vehicle has traveled a certain distance irrespective of its speed, means for transmitting a second impulse to said receiving means to cause the circuit of said magnet to be instantly broken, and manually operable means for restoring said circuit under either circumstance, before the retarding means can become effective.
55. In a system of vehicle control, speed control equipment partly on a trackway divided into sections and partly on the vehicle, retarding means on the vehicle, a controlling magnet having a circuit for maintaining it operated to prevent the retarding means becoming effective, means at the exit end of each trackway section for transmitting and on the vehicle for receiving an impulse to cause said circuit to be opened only after the vehicle has traveled a certain distance irrespective of its speed, means for transmitting a second impulse to said receiving means to cause the circuit of said magnet to be instantly broken, and manually operable means for restoring said circuit under either circumstance, before the retarding means can become effective.
60. In a system of vehicle control, speed control equipment partly on a trackway divided into sections and partly on the vehicle, retarding means on the vehicle, a controlling magnet having a circuit for maintaining it operated to prevent the retarding means becoming effective, means at the exit end of each trackway section for transmitting and on the vehicle for receiving an impulse to cause said circuit to be opened only after the vehicle has traveled a certain distance irrespective of its speed, means for transmitting a second impulse to said receiving means to cause the circuit of said magnet to be instantly broken, and manually operable means for restoring said circuit under either circumstance, before the retarding means can become effective.
65. In a system of vehicle control, speed control equipment partly on a trackway divided into sections and partly on the vehicle, retarding means on the vehicle, a controlling magnet having a circuit for maintaining it operated to prevent the retarding means becoming effective, means at the exit end of each trackway section for transmitting and on the vehicle for receiving an impulse to cause said circuit to be opened only after the vehicle has traveled a certain distance irrespective of the vehicle speed, means for transmitting a second impulse to said receiving means to cause the circuit of said magnet to be instantly broken, and manually operable means for restoring said circuit under either circumstance, before the retarding means can become effective.
70. In a system of vehicle control, speed control equipment partly on a trackway divided into sections and partly on the vehicle, retarding means on the vehicle, a controlling magnet having a circuit for maintaining it operated to prevent the retarding means becoming effective, means at the exit end of each trackway section for transmitting and on the vehicle for receiving an impulse to cause said circuit to be opened only after the vehicle has traveled a certain distance irrespective of the vehicle speed, means for transmitting a second impulse to said receiving means to cause the circuit of said magnet to be instantly broken, and manually operable means for restoring said circuit under either circumstance, before the retarding means can become effective.
75. In a system of vehicle control, speed control equipment partly on a trackway divided into sections and partly on the vehicle, retarding means on the vehicle, a controlling magnet having a circuit for maintaining it operated to prevent the retarding means becoming effective, means at the exit end of each trackway section for transmitting and on the vehicle for receiving an impulse to cause said circuit to be opened only after the vehicle has traveled a certain distance irrespective of the vehicle speed, means for transmitting a second impulse to said receiving means to cause the circuit of said magnet to be instantly broken, and manually operable means for restoring said circuit under either circumstance, before the retarding means can become effective.
- for restoring said circuit under either circumstance, before the retarding means can become effective.
36. In a train control apparatus, the combination with a valve device operated upon a reduction in fluid pressure for effecting an application of the brakes, and electrically controlled means adapted upon deenergization to vent fluid pressure from said valve device, of means operated by the venting of fluid pressure from said valve device for opening a circuit through which said electrically controlled means may be maintained energized.
80. 37. In a train control system, an electropneumatic valve, a vehicle speed governor having contacts controlled thereby included in an energizing circuit for said valve, means for selectively determining at what vehicle speed the governor will bring about the opening of said contacts, brake control mechanism set into operation to apply the vehicle brakes consequent to the deenergization of said electropneumatic valve, a second pair of contacts operative coincident with an automatic brake application, a set of manually operative contacts one pair of which are included in said circuit, a control circuit including another pair of contacts of the set and an acknowledging magnet controlled thereby to forestall an initiated automatic brake application, only if operated before said second pair of contacts have operated.
90. 38. In a train control system, an electro-pneumatic valve, a circuit normally maintaining said valve closed to prevent a brake application, means for automatically opening said circuit, means for delaying the brake application taking place for a predetermined period of time after the circuit is opened, and a manually operable acknowledging lever operated to cause the reclosure of said circuit before the expiration of said 95 predetermined period of time and operated to cause the closure of said circuit after the predetermined period has expired only if the train has come to a complete stop.
100. 39. In a train control system applied to a railway system having its trackway divided into blocks, a pair of cab carried signals, means for actuating said signals at the exit of a block when the traffic conditions ahead are unfavorable, manually controlled means operable to retire only one of said signals, and means for temporarily preventing the retiring of said one signal after the expiration of a definite interval of time following the first change.
105. 40. In a train control system, vehicle carried visual and audible signals together with apparatus for controlling the brakes of the vehicle, pairs of trackway magnets spaced at points along the trackway for transmitting controlling influences from the trackway to the vehicle, a relay carried by the vehicle responsive to said influences to variably change the condition of said signals and to initiate the operation of said brake controlling apparatus and means for manually changing the condition of only one of said signals 110 and for preventing a brake application occurring under certain conditions.
110. 41. In a train control system, a normally energized electro-pneumatic valve for normally preventing an automatic brake application occurring, means for causing the magnet of such valve to become deenergized, means for delaying a brake application occurring for a definite interval after the deenergization of such magnet occurs, and a cab carried readily accessible manu- 115
120. 42. In a train control system, a normally energized electro-pneumatic valve for normally preventing an automatic brake application occurring, means for causing the magnet of such valve to become deenergized, means for delaying a brake application occurring for a definite interval after the deenergization of such magnet occurs, and a cab carried readily accessible manu- 125
125. 43. In a train control system, a normally energized electro-pneumatic valve for normally preventing an automatic brake application occurring, means for causing the magnet of such valve to become deenergized, means for delaying a brake application occurring for a definite interval after the deenergization of such magnet occurs, and a cab carried readily accessible manu- 130
130. 44. In a train control system, a normally energized electro-pneumatic valve for normally preventing an automatic brake application occurring, means for causing the magnet of such valve to become deenergized, means for delaying a brake application occurring for a definite interval after the deenergization of such magnet occurs, and a cab carried readily accessible manu- 135
135. 45. In a train control system, a normally energized electro-pneumatic valve for normally preventing an automatic brake application occurring, means for causing the magnet of such valve to become deenergized, means for delaying a brake application occurring for a definite interval after the deenergization of such magnet occurs, and a cab carried readily accessible manu- 140
140. 46. In a train control system, a normally energized electro-pneumatic valve for normally preventing an automatic brake application occurring, means for causing the magnet of such valve to become deenergized, means for delaying a brake application occurring for a definite interval after the deenergization of such magnet occurs, and a cab carried readily accessible manu- 145
145. 47. In a train control system, a normally energized electro-pneumatic valve for normally preventing an automatic brake application occurring, means for causing the magnet of such valve to become deenergized, means for delaying a brake application occurring for a definite interval after the deenergization of such magnet occurs, and a cab carried readily accessible manu- 150

ally operable element having equipment controlled thereby to bring about the reenergization of the magnet of said valve only if operated before said predetermined interval has expired, or after 5 the vehicle has been brought to a standstill.

42. In a train stop system, an automatic brake valve, a magnet normally energized to prevent said brake valve from functioning, three cab signals for indicating traffic conditions, a relay for 10 controlling the said magnet and signals, and an acknowledging contact set for controlling said relay.

43. In the vehicle equipment of a train stop system, an automatic brake valve, a magnet normally energized to prevent said brake valve from functioning, three cab signals for indicating traffic conditions, a relay operable by magnetic impulses transmitted from a source exterior to the vehicle for controlling the said magnet and signals, and an acknowledging contact set for also controlling said relay. 80
